CERTIFICATE OF CORRECTION

PATENT NO. : D813,413 S
APPLICATION NO. : 29/567780
DATED : March 20, 2018
INVENTOR(S) : Kramer

Page 1 of 1

It is certified that error appears in the above-identified patent and that said Letters Patent is hereby corrected as shown below:

This certificate supersedes the Certificate of Correction issued June 19, 2018. The certificate is vacated since correction to Applicant is not proper. The Applicant name on front page of patent was taken from the Applicant section of the Application Data Sheet (ADS), or the applicant was the inventor(s) if no applicant was specified in the ADS. No request to change the applicant in compliance with 37 CFR 1.46(c) was filed during the pendency of the application. Since what is listed on the patent is correct relative to the patent application file record from which the patent issued, no correction is in order under 37 CFR 1.322 or 1.323. The Certificate of Correction dated June 19, 2018, was published in error and should not have been issued for this patent.

Signed and Sealed this
First Day of January, 2019

Andrei Iancu
Director of the United States Patent and Trademark Office
